UNITED STATES PATENT OFFICE.

SIMEON S. JACKSON, OF HYDE PARK, BOSTON, MASSACHUSETTS, ASSIGNOR TO THE STAFFORD COMPANY, OF READVILLE, MASSACHUSETTS, A CORPORATION OF MASSACHUSETTS.

FILLING-FEELER MECHANISM FOR LOOMS.

Application filed November 14, 1923. Serial No. 674,685.

To all whom it may concern:

Be it known that I, SIMEON S. JACKSON, a subject of Great Britain, residing at Hyde Park, Boston, in the county of Suffolk, State 5 of Massachusetts, have invented a certain new and useful Improvement in Filling-Feeler Mechanism for Looms, of which the following is a specification, reference being had therein to the accompanying drawings.

10 The invention has relation in general to the depletion-detecting mechanisms, commonly termed feeler mechanisms, which are employed in looms for the purpose of fore-stalling complete exhaustion of the supply of 15 weft or filling contained in the working shuttle upon the lay-beam of a loom. These mechanisms in general are contrived to "call," or "indicate," or "initiate," as it is variously termed, a change in the operation 20 of the loom, upon detecting that the progressive depletion of the said supply has reached a stage decided upon as a minimum. This change involves in some cases automatic replenishing of the working supply 25 of the weft or filling without stoppage of the loom; in others it involves stoppage of the loom, with automatic replenishment during the stoppage, followed by automatic re-starting of the loom.

30 The invention relates more especially to feeler mechanisms of the side-slipping class. A feeler mechanism of this class has a feeler member which enters the shuttle during a feeling action to contact with the wound 35 mass of filling therein, this member being designed to slip or swing lengthwise of the shuttle while in contact with the shuttle-contents. It is held from such movement by engagement with the wound mass within the 40 shuttle so long as an adequate supply of weft or filling for continued weaving remains, but slips or swings sidewise, that is, lengthwise of the shuttle, in the absence of a sufficient supply, and through the change-calling 45 mechanism of the loom calls the change aforesaid.

The object of the invention is to provide a feeler mechanism of the side-slipping class of extremely simple construction, inexpensive, light and easy in its action, and easily kept in practical working condition.

The invention consists in a feeler mechanism of the class aforesaid characterized by the special construction, relation and con-

nection of parts, and mode of operation, 55 hereinafter described, and comprising the combinations which are set forth in the claims at the close of this specification.

A feeler mechanism in accordance with the invention is shown in the accompanying 60 drawings, in which,—

Fig. 1 is a plan view showing the said mechanism mounted at one end of the breast-beam of a loom, with the parts in their 65 normal positions.

Fig. 2 is a view in vertical section on line 2—2 of Fig. 1, looking in the direction indicated by the arrows.

Figs. 3 and 4 are views in vertical section made on lines 3—3 and 4—4, respectively, 70 of Fig. 1, looking in the directions indicated by the arrows.

Having reference to the drawings,—

The feeler-member 1 is conveniently formed with a straight portion or shank 75 adapted to slide in a direction fore-and-aft of the loom in guides 2, 3, provided in up-standing lugs 4, 5, respectively, on the feeler-stand 6 which is fixed on the arm 7 fastened to the usual bracket 71 extending outward from one end of a loom breast-beam 8. The rearward end of the feeler-member is provided as usual with serrations 11 to engage more positively with the turns of filling 85 which comprise the wound mass of weft or filling contained in the working shuttle (not shown) of the loom. The guide 2 occupied by the intermediate portion of the shank of the feeler-member 1 is a guideway of considerable width, so that the feeler-member 90 may swing or slip laterally in a horizontal plane within the said guideway upon occasion; the cover 12 is provided to bridge such guideway and hold the feeler-member therein, being itself secured by screws 13, 13, 95 to the lug 4. The front guide 3 is formed to permit slight lateral swinging action of the feeler-member.

The feeler-member 1 is held rearward in its normal presentation position shown in 100 Fig. 1 by means of an expanding spiral spring 14 which surrounds its shank and is confined between the forward lug 5 on feeler-stand 6 and a collar 15 which is secured to the feeler-member 1 by a clamping screw 16. The 105 cover 12 has formed at its inward end a forwardly projecting cam surface 17 with which a nose 18 upon the collar 15 engages, when

spring 14 gives the feeler-member its rearward presentation position, the said cam acting to hold the feeler-member over against the right-hand wall of guide 2, as shown.

5 A connection 19, comprising simply a rod or wire, serves to combine the feeler-member 1 with the latch-controlling bolt 27 described hereinafter. This connection 19 is combined with the collar 15 fixed on the feeler-member, by having its downturned end 20, Fig. 4, put through a hub 21 formed on the collar 15 and secured by a cotter-pin through said end below the collar. It is provided with a collar 22 fixed thereon by a clamping screw 23, and a contracting spring 24, engaged at one end with such screw 23 and at the other anchored by a screw 25 to a small stand 26 mounted on the breast-beam 8, exerts upon the collar 15 and hence upon the 10 feeler-member 1 a lateral pull inwardly of the loom. When the feeler-member 1 is rearward, its tendency to slip or swing sidewise under this lateral pull is resisted by the engagement of the cam surface 17 with the nose 18 on the collar 15, and the feeler-member 1 occupies the position shown, at the right-hand side of the guide 2. When the lay comes forward in beating up, and the shuttle-contents engage the filling-engaging portion 15 of the feeler-member, sliding the feeler-member forward in guides 2 and 3, the nose 18 will be carried forward out of contact with the cam surface 17, but if there remains a sufficient supply within the shuttle for continued weaving, the filling-engaging portion 20 with its serrations 11 will catch on the turns of filling and prevent the feeler-member from swinging laterally inward in obedience to the pull of spring 24. That is, the 25 feeler-member will slide forward in guides 2 and 3 under the push of the shuttle-contents, moving only in the direction of its length and with no side-slipping action; no material movement of connection 19 occurs 30 in the direction of the latter's length.

At its inward or left-hand end the connection 19 is combined with the latch-controlling bolt 27, the latter being mounted in a bore extending transversely through a small 35 stand 26, the downturned end 28 of the connection being hooked into a suitable one of several holes 29, 29, which are provided in the bolt 27 and secured by a cotter-pin 30. The small stand 26 is located close to the 40 latch 31, which is a familiar member of the change-calling mechanism (not shown), it being arranged for cooperation as usual with the vibrating weft-hammer 32. The said stand 26 has a notch 33 extending fore-and-aft which intersects the bore in which the 45 bolt 27 slides, and in this notch rests an extension 34 from the side of the latch 31. This extension may be of any suitable form, such as that shown herewith, where a piece of 50 round wire or stock is threaded at one end,

put through a hole in the latch 31, and fixed by jam-nuts 35, 35, applied at opposite sides of the latch. The wire or stock extends outwardly from the latch, then downwardly and rearwardly, and is turned up slightly at its 70 rearward end. It rests within the notch 33 and upon the top surface of the bolt 27, so that the latch 31 is held up out of position for being engaged by the shoulder 36 on the weft-hammer 32. The bolt 27 is notched in 75 its upper side at 37, just outwardly of the point where the extension 34 normally rests upon it.

When the wound mass of filling within the shuttle has become substantially depleted, so that the few remaining turns of filling are no longer able to hold the feeler-member from slipping sidewise on the nearly bare filling-carrier under the pull of spring 24 when the feeler-member 1 is 80 pushed forward in a feeling action so that the nose 18 on the collar 15 is free of the cam 17, and the feeler-member swings inwardly of the loom to the left-hand side of guideway 2, about the forward guideway 3 85 as a center, this swinging movement involves a corresponding lengthwise movement of the connection 19. This in turn moves bolt 27 inwardly so that the cut-away place 37 therein is carried beneath the extension 34 90 of the latch. The extension 34 immediately drops into the cut-away place 37, and the latch 31 drops onto the vibrating weft-hammer 32, where its rearward edge 38 is engaged by the shoulder 36 on the weft-hammer, and the latch is driven forward to activate the change-calling mechanism and call 95 the change.

After the feeler-member has slipped sidewise to call the change as just described, it 100 is restored to its normal presentation position, that is to say, straightened up again, by the reengagement of cam 17 and nose 18, as the feeler-member moves rearwardly with the receding lay. This action draws the 105 bolt 27 outwardly, namely to the right, and withdraws the cut-away place 37 from under the notch 33. Thus, when the latch 31 returns as the weft-hammer 32 swings rearward, and its extension 34 reenters the notch 110 33, the rounded rear end of such extension 34 rides up and over the rounded top surface of bolt 27 at a point where such bolt is of full diameter, and so lifts the latch out of engagement with the weft-hammer 32. 115 The whole feeler mechanism is thus automatically reset, and ready to begin again 120 the feeling action upon a fresh supply of filling within the shuttle.

What is claimed as the invention is,— 125

1. In a filling-feeler mechanism comprising a feeler-member actuated forwardly through engagement of the shuttle, contained filling-mass therewith spring-actuated rearwardly into initial position and movable

sidewise for detecting purposes, fixed guides occupied by the feeler-member permitting sidewise detecting movement of the feeler-member, a resetting cam, a latch which is an element of change-calling mechanism, and a weft-hammer, the combination therewith of a latch-supporting bolt which when moved endwise releases the said latch, a collar fixedly attached to the 10 feeler-member, engaging with the rear guide to limit the movement of the feeler-member rearward, and with the cam to effect resetting, and a wire connecting said collar with said bolt and swinging in unison with the 15 fore-and-aft movements of the feeler-member.

5 into intial position and movable sidewise for detecting purposes, fixed guides occupied by the feeler-member permitting sidewise detecting movement of the feeler-member, a resetting cam, a latch which is an element of change-calling mechanism, and a weft-hammer, the combination therewith of a sliding 20 latch-controlling bolt, a projection on the feeler-member engaging with the rear guide to limit the movement of the feeler-member rearward, and with the cam to effect resetting, and a wire connecting said bolt to the 25 feeler-member, swinging in unison with the fore-and-aft movements of the feeler-member, and moving the bolt endwise when side-slipping of the feeler-member occurs.

2. In filling-feeler mechanism comprising a feeler-member spring-actuated rearwardly

SIMEON S. JACKSON.
